UNITED STATES PATENT OFFICE.

OTTO S. PIKE, OF MALDEN, MASSACHUSETTS, ASSIGNOR TO AMERICAN PNEUMATIC SERVICE COMPANY, OF DOVER, DELAWARE, A CORPORATION OF DELAWARE.

PNEUMATIC CARRIER.

SPECIFICATION forming part of Letters Patent No. 760,701, dated May 24, 1904.

Application filed November 3, 1902. Serial No. 129,807. (No model.)

To all whom it may concern:

Be it known that I, OTTO S. PIKE, of Malden, in the county of Suffolk and State of Massachusetts, have invented certain new and useful 5 Improvements in Pneumatic Carriers, of which the following is a specification.

My invention relates to new and useful improvements in pneumatic carriers, and especially to buffer-heads for such carriers.

10 My invention consists of certain novel features hereinafter described, and particularly pointed out in the claims.

In the accompanying drawings, which illustrate a construction embodying my invention, Figure 1 is a perspective view of a carrier provided with the improved buffer-head. Fig. 2 is a front view of a carrier, showing the improved buffer-head. Fig. 3 is a side view of the buffer-head in section. Fig. 4 is a front 20 view of a modification shown in Fig. 5. Fig. 5 is a side view, partly in section, of a modification of the improved buffer-head.

Like letters of reference refer to like parts throughout the several views.

25 A represents a carrier for pneumatic-despatch transit systems provided with the usual contact-rings B of any suitable material near the ends of the carrier. As shown in Fig. 3, the shell A is provided on its front end with an inwardly-turned flange C, and supported on this flange is a concave receptacle D, having an outwardly-extending flange E. Within 30 this receptacle D is a backing of felt or other elastic material F and a facing of leather made up of four disks G, H, I, and J, which disks are fastened together by a circular row of stitching K. The disks I and J are larger in 35 diameter than the disks G and H.

In assembling the buffer-head the felt back- 40 ing F or other yielding material is placed in the receptacle D and the disks G, H, I, and J are placed on said yielding material, and the concentric ring L is then slipped over the disks G and H and rests on the disk I, as 45 shown, and then the flange C and flange E and the ring L are securely fastened together by a circular row of rivets M, thereby holding

the leather facing and felt backing firmly in place on the front end of the carrier.

Referring to Figs. 4 and 5, which illustrate 50 a modification, A' represents a carrier for pneumatic transit systems having the usual contact-rings B' (one of which is shown) at the front end of the carrier. The front end of the shell of the carrier A' is turned in- 55 wardly and formed into a concave receptacle D', so that the shell and receptacle are of one piece. Within the receptacle D' is a backing of felt or other elastic material F' and a leather facing made up of four disks G', H', I', and 60 J', and these disks are fastened together by a circular row of stitching K'. The disks G' and H' are smaller in diameter than disks I' and J'. In making up the buffer-head above described the backing F' is placed in the re- 65 ceptacle D', the disks G', H', I', and J' are placed on said yielding material, the concentric ring L' is then placed over the disks G' and H', resting on the disk I', as shown, and the flange C' and flange E' and the ring L' are then securely 70 fastened together by a circular row of rivets M', and the leather facing and felt backing are thus held securely in place on the front end of the carrier.

Having thus described the nature of my in- 75 vention and set forth a construction embodying the same, what I claim as new, and desire to secure by Letters Patent of the United States, is—

1. In a pneumatic carrier, a receptacle lo- 80 cated in one end of the carrier, a yielding buffer-head of different diameters located in said receptacle, and an annular ring of less diame- 85 ter than the larger diameter of said yielding buffer-head secured to said carrier for holding the buffer-head in position.

2. In a pneumatic carrier, a receptacle lo- 90 cated in one end of the carrier, a buffer-head in said receptacle consisting of elastic mate- 95 rial in said receptacle and disks of leather of different diameters sewed together, and a ring of less internal diameter than the larger leather disks secured to said carrier for holding the buffer-head in position.

3. In a pneumatic carrier, a receptacle located in one end of the carrier, a buffer-head in said receptacle consisting of elastic material in said receptacle and disks of leather of 5 different diameters connected together, and a ring of less internal diameter than the larger leather disks secured to said carrier for holding the buffer-head in position.

In testimony whereof I have signed my name to this specification, in the presence of two subscribing witnesses, this 30th day of October, A. D. 1902.

OTTO S. PIKE.
